UNITED STATES PATENT OFFICE

WILLIAM S. SPENCE, OF MILWAUKEE, WISCONSIN, ASSIGNOR TO RUNDLE-SPENCE MFG. CO., OF MILWAUKEE, WISCONSIN, A CORPORATION OF WISCONSIN

DESIGN FOR A DRINKING FOUNTAIN

Application filed August 26, 1929. Serial No. 32,533. Term of patent 14 years.

To all whom it may concern:

Be it known, that I, WILLIAM S. SPENCE, a citizen of the United States, residing at Milwaukee, in the county of Milwaukee and State of Wisconsin, have invented a new, original, and ornamental Design for Drinking Fountains, of which the following is a specification, reference being had to the accompanying drawing, forming part thereof.

In the drawing Fig. 1 is a side view of the drinking fountain showing my new design; Fig. 2 is a top view thereof; and Fig. 3 is a front view.

I claim:

The ornamental design for a drinking fountain, as shown.

WILLIAM S. SPENCE.
